UNITED STATES PATENT OFFICE

ROBERT DAVOL BUDLONG, OF CHICAGO, ILLINOIS, ASSIGNOR OF ONE-HALF TO JAMES H. ROOK, OF CHICAGO, ILLINOIS

DESIGN FOR A COMBINATION BATHROOM UNIT

Application filed April 14, 1933. Serial No. 47,785. Term of patent 3½ years.

To all whom it may concern:

Be it known that I, ROBERT DAVOL BUDLONG, a citizen of the United States, residing at Chicago, in the county of Cook and State of Illinois, have invented a new, original, and ornamental Design for a Combination Bathroom Unit, of which the following is a specification, reference being had to the accompanying drawing, forming part thereof.

The figure is a perspective view of the combination bathroom unit, showing my new design.

I claim:

The ornamental design for a combination bathroom unit, as shown.

ROBERT DAVOL BUDLONG.
